UNITED STATES PATENT OFFICE.

ALEC J. GERRARD AND PARVIN WRIGHT, OF CHICAGO, ILLINOIS.

WIRE TENSIONING AND TWISTING MACHINE.

Application filed March 7, 1922. Serial No. 541,777.

To all whom it may concern:

Be it known that we, ALEC J. GERRARD and PARVIN WRIGHT, respectively a subject of the King of Great Britain and a citizen 5 of the United States, each residing at Chicago, in the county of Cook and State of Illinois, have invented certain new and useful Improvements in Wire Tensioning and Twisting Machines; and we do hereby 10 declare the following to be a full, clear, and exact description of the invention, such as will enable others skilled in the art to which it appertains to make and use the same.

15 This invention relates to wire tensioning and twisting machines, and has for its object to provide a machine of this character which will be simple in construction, comparatively inexpensive to manufacture, and 20 more efficient in action than those heretofore proposed.

With these and other objects in view, the invention consists in the novel details of construction and combinations of parts more 25 fully hereinafter disclosed and particularly pointed out in the claims.

This invention constitutes an improvement over that disclosed in our copending application, Serial No. 418634, filed Oct-30 tober 22, 1920, and entitled "Wire tensioning and twisting machine."

Referring to the accompanying drawings forming a part of this specification, in which like numerals designate like parts in all the 35 views;

Figure 1 is a diagrammatic front elevational view of a machine made in accordance with this invention;

Figure 2 is a detail sectional view taken 40 on the line 2-2 of Figure 1, looking in the direction of the arrows;

Figure 3 is a side view partially broken away, of the rotary cutter;

Figure 4 is an end elevational view of 45 the parts shown in Figure 1, as seen from the left of said figure;

Figure 5 is a fragmentary vertical sectional view taken approximately on the line 5-5 of Figure 4, looking in the direction 50 of the arrows;

Figure 6 is a view of a wire holding post detached from the machine;

Figure 7 is an end view of the parts 55 shown in Figure 6, with the deformed end of a wire in place;

Figure 8 is a transverse sectional view

taken approximately on the line 8-8 of Figure 5, looking in the direction of the arrows;

Figure 9 is a transverse sectional view 60 taken approximately on the line 9-9 of Figure 1, looking in the direction of the arrows;

Figure 10 is a diagrammatic plan view 65 of the wire knot formed by this machine; and

Figure 11 is a sectional detail view illustrating the operation of the cutter lever and its associated parts.

1 indicates any suitable base provided 70 at one end with an upright extension 2, in which is journalled a shaft 3 provided at one end with the crank handle 4 and carrying upon its other end a suitable pinion 5 (see Figures 1 and 5). The base 1 at the end 75 opposite the extension 2 is provided with an integral upright housing 6 constituting the casing for the twisting gear train comprising the pinion 5, the intermediate gear 7, which is rotatably mounted on the stud 8 80 carried in the said housing 6, and the twisting pinion 9, as will be clear from the drawings.

An end plate or member 10 conforming 85 substantially in shape with that of the housing 6 is secured to the base member 1 and to said housing by means of suitable bolts 11 and together with the said housing forms a journal for the hubs or extensions 12 and 13, with which the twisting pinion 9 is 90 provided.

The said hubs or extensions 12 and 13, as is usual in this type of twisting mechanism are provided with slots 14 and 15 respectively, of a width of at least twice the diameter of the wire 47, which is to be employed in the machine. These slots are connected by the slot 16 in the pinion 9 which latter slot is of reduced width, preferably only exceeding the diameter of the wire sufficiently to permit its ready insertion and withdrawal. The housing 6 as well as the end member 10, are also provided, as best shown in Figures 1, 4 and 9, with slots 17 and 18 respectively, of a width equal to at least twice the diameter of the wire. 95 100 105

The member 10 is provided with the rigid wire holding post 20 having a horizontal slot 21 therein, adapted to receive the wire, and the member 1 is likewise provided with the rigid post 22 also having a horizontal slot 23 to receive the wire. The said post 110

22 may be surrounded by the oscillating sleeve 24, see Figures 1, 3 and 8, having a cutting edge 25 adapted to sever one strand of the wire and the said cutting sleeve 24 may be actuated in any suitable manner, as, for example, by the finger or lever 26, rigid with the said sleeve, see Figures 5, 8 and 9, and which projects through a slot 27 in the housing 6, see Figures 8 and 9, in the path of a pin or lug 28 carried by the intermediate gear 7, see Figures 9 and 11.

Referring more especially to Figures 1 and 2, the wire tensioning means which forms an essential part of this invention comprises a hand lever 30 pivoted upon the stud or bolt 31 secured in the upright web 32 of the frame 1. Also mounted upon the said stud 31 adjacent the lever 30 is a ratchet wheel 33, and associated with said ratchet wheel is a wire gripping V-shaped groove 40 having the tangentially disposed recesses 41 adapted to receive the end 36 of the wire.

25 The hand lever 30 has pivotally secured thereto as at 46 a dog 48 having associated therewith a suitable spring 50 adapted to normally maintain said dog in contact with the teeth of the ratchet wheel 33. A suitable detent 51 may be pivoted as at 52 to the web 32 of the frame 1 and controlled by a suitable spring 53 for the purpose of preventing reverse motion of the ratchet wheel 33 and its associated parts.

35 The mechanism employed in this invention for insuring at the end of the twisting operation the alinement of the slots 14, 15 and 16 of the twister pinion 9 with the slots 17 and 18 of the housing 6 and end member 10, comprises a lever 55 pivotally secured to the upper portion of the end member 10 by the stud 56. One end of the said lever 55 is bent downwardly as at 57 and passes through a hole at one end of the pin 58 slidably mounted in a block 59 and extending through an elongated slot 60 in the end plate 10, see Figures 4 and 11. The end 61 of the said pin 58 is preferably beveled as shown in Figure 11, and is adapted 50 to enter a recess or hole 62 in the large intermediate gear 7, as will be clear from the drawings.

The block 59 above referred to is provided with the vertical pins 63 and 64 slidably mounted in the bosses integral with the end plate 10, and the said pin 63 may have associated with it a suitable compression spring 65 for the purpose of maintaining the block 59 in such a position in the slot 60 as will facilitate the locking movements of the pin 58, which latter movements are under the control of a suitable spiral spring 66, see Figure 5.

Upon the completion of the twisting operation, it is frequently found difficult to

extract the wire from the slots of the twister pinion by hand and it is an important feature of this invention that there is provided a mechanical means for assisting in this. This said means as here shown comprises 70 a curved lever member 70 pivoted as at 71 to the rear end 37 of the post 20, as will be clear from Figures 1, 4 and 5. Said lever 70 is also provided with the curved operating handle 77 which is located well inside 75 the boss 78 which is integral with the member 10, and is therefore protected from injury by said boss when the machine is dropped end on, as experience shows often happens in practice. The center of gravity 80 of the lever 70 is also to the right of the pivot 71, as seen in Figure 4, and therefore when said lever is accidentally raised it automatically returns to the position shown in said figure, and thus normally keeps the wire ejecting member 74 in its retracted position. The extreme lower and forward portion 80 of said lever 70 is of the hook or notched shape shown, and normally lies under the influence of gravity in front of 90 the two bights of the tie wire, and thus holds them in place in the slots 21 and 81 of the post 20, as illustrated.

The operation of this machine will be clear from the foregoing, but may be briefly 95 summarized as follows: The machine is placed upon the top surface of the box or other package around which the wire is to be fastened, and a deformed end 84 of the wire 47 having the shoulder 85 and depression 86, is introduced into the smaller slot 81 carried by the pin or post 20, see Figures 4, 6 and 7.

The bight 88 of said wire is now carried toward the right, as seen in Figure 1, 105 through the slots 18, 14, 16, 15 and 17, through the slot 23 in the post 22, and around the package until its bight 89 is brought back to the post 20 and passed through the wider slot 21 in said post, and through said slots 18, 14, 16, 15, 17 and 110 23, to and around the groove 40 with which the ratchet 33 is provided. From said groove 40, the end 36 of the bight 89 is passed into a slot 41 and thus held firmly 115 while said ratchet 33 is turned by the handle 30 to put a tension on the wire. After a sufficient tightening of the wire has thus been had, the lever 55 is depressed to withdraw the pin 58 from the hole 62 in the gear 7, and the handle 4, and shaft 3 is turned which turns the pinion 5, gear 7, and twisting pinion 9, thus twisting the two bights 88 and 89 of the wire together, as 120 illustrated in Figure 10. As the gear 7 continues to revolve, during its twisting action, it carries with it the lug 28, which just before the completion of said twisting action strikes the end of the lever 26, see Figure 11, and thus rotates the cutter 24 which 125 130

is provided with a cutting edge at 90 opposite the bight 89 and a slot at 91 opposite the bight 88.

The bight 89 is accordingly severed at the 5 end of the twisting operation while the bight 88 is left undisturbed. The original pull on the bight 88 during the tensioning operation causes the shoulder 92 (see Figures 6 and 7) of the slot 81 to press on the shoulder 85 of 10 the wire, and to thus bend the end 84 of said wire into its dotted line position shown in Figure 7, by reason of the lower edge 93 of the slot 81 being cut away. This bending down of the end 84 of the wire as indicated 15 in Figure 10, causes the same to lie down snugly against the bight 89 of the knot in Figure 10, and prevents it tearing other packages which may be slid over said knot during shipment. In the same way, the 20 rotary movement of the cutting edge 90 (Figure 3) bends down the severed end of the bight 89 and causes it to lie snugly against the bight 88 of the knot, as will be apparent from Figure 10, thus preventing 25 said severed end from tearing packages moved over the same.

After the cutter lever has been moved by the lug 28 in the manner disclosed, it is immediately returned to its normal position by 30 the flat member 95 having a tapered end fitting the groove 96 in said lever, see Figures 9 and 11. Said member 95 is provided with the extension 97 and is controlled by the spring 98, as will be readily understood.

35 As the gear 7 continues to turn its hole 62 after a complete revolution will again register with the pin 58, and the end 61 of said pin will again enter said hole under the influence of the spring 66, thus stopping the 40 twisting slot 16 in a position to register with its companion slots 17 and 18. Upon now throwing the lever 70 to the left, as seen in Figure 4, the pusher 74 will forcibly eject the twisted knot from the machine.

45 It will now be clear that when the pin 58 is in the hole 62, that the slot 16 will always be in position to either receive or to discharge the wire.

It is an important feature of this invention that the lever 70 normally, under the 50 action of gravity, occupies its full line position shown in Figure 4, for it often happens that the operator accidentally displaces a bight 88 or 89 from the post 20 before the 55 twisting operation, and when this occurs, said lever 70 automatically restores the wire to its proper position. Further, the forward edge of the hook portion 80 of said lever 70 is inclined as shown, which aids the operator 60 to quickly guide the wire into the slot 21.

What is claimed is:

1. In a wire tying machine the combination of a frame provided with a plurality

of wire receiving slots; twisting means comprising a slotted post and rotatable slotted means carried by said frame adapted to twist the wire; means adapted to insure the alinement of the slots of said twisting means with the slots of said frame at the completion of the twisting operation; and means 65 movable longitudinally of said post adapted to positively disengage the twisted wire from said post at the end of the twisting operation, substantially as described.

2. In a wire tying machine the combination of a frame provided with a plurality of wire receiving slots; means adapted to exert a tension on the wire; twisting means comprising a slotted post and a rotatable slotted means carried by said frame adapted to 70 twist the wire; means adapted to insure the alinement of the slots of said twisting means with the slots of said frame at the completion of the twisting operation; automatic means adapted to sever the wire; and means 75 guided by said post adapted to positively disengage the twisted wire from all of said slots, substantially as described.

3. In a wire tying machine the combination of a wire twisting means comprising a 80 slotted post and a slotted pinion; a gravity actuated latch adapted to hold parallel bights of wire in the slots of said post and pinion; a tensioning means comprising a ratchet; means to operate said ratchet; 85 means movable longitudinally of said post to disengage the twisted wire therefrom; and a cutter for automatically severing the wire at the end of the twisting operation, 90 substantially as described.

4. In a wire tying machine the combination of a twisting means comprising a slotted post and pinion adapted to twist two bights of a wire together; a gravity actuated latch associated with said post adapted to 95 hold said bights in said post and pinion; means comprising a ratchet and lever to put one of said bights under tension; means for automatically severing one of said bights at the end of the twisting operation; and means 105 operated by said latch to forcibly eject the twisted wire, substantially as described.

5. In a wire tying machine the combination of means adapted to hold two bights of a wire in parallel relation; means to twist 110 said bights together while so held; means associated with said first named means to forcibly remove the twisted bights from the machine; means to automatically stop the twisting means in a predetermined angular 115 position; and means to automatically sever the wire, substantially as described.

In testimony whereof we affix our signatures.

ALEC J. GERRARD,
PARVIN WRIGHT.
